UNITED STATES PATENT OFFICE.

JOHN F. PAGENDARM, OF OAKLAND, CALIFORNIA, ASSIGNOR TO AMERICAN WOOD-LITE CORPORATION, OF SAN FRANCISCO, CALIFORNIA, A CORPORATION OF ARIZONA.

UNIVERSAL FOCUSING DEVICE.

Application filed November 25, 1925. Serial No. 71,278.

This invention relates to focusing devices for incandescent lamps especially intended for use with light projectors.

The object of the invention is to provide a simple and inexpensive device which will permit of ready adjustment of the lamp so as to focus the same properly with respect to the reflector. The device permits of both axial and angular adjustment of the lamp, and includes a single element for locking the lamp socket in adjusted position.

One form which my invention may assume is exemplified in the following description and illustrated in the accompanying drawings, in which

Fig. 1 shows a vertical central sectional view of a headlight equipped with a focusing device in accordance with my invention;

Fig. 2 shows a plan view of the device of Fig. 1 with the upper portion of the lamp housing removed.

The headlight herein illustrated includes a casing 10 and a reflector 11. The focusing device is provided with a base 12 for securing it to the casing. Secured to this base is a seat 13 screw-threaded on its exterior. Fitted against the seat 13 is a spherical element 14 having an opening to slidably receive a tubular member 15 which forms the socket for the lamp 16. The spherical member 14 is constructed of spring metal and is provided with slits 16^a extending inwardly from opposite ends past the middle thereof, so as to contract and grip the lamp socket when clamped against its seat. The spherical member is clamped to its seat by means of a ring 17 which is threaded onto the seat 13, and has a flange 18 at its opposite end contacting with the sides of the spherical member. When the clamping ring 17 is slackened off, the spherical member 14 expands and allows the socket 15 to be moved axially for the purpose of adjusting the position of the lamp. Angular adjustment of the lamp is provided by reason of the spherical member moving angularly upon its seat. When the

lamp is in the correct position the ring 17 is tightened, thereby locking the spherical member upon its seat and simultaneously contracting it so as to grip the socket tightly.

Any desired adjustment is quickly and easily obtained, and the device is simple and inexpensive to construct. The clamping ring 17 serves to lock the spherical member to its seat and to cause the latter to grip the socket, so that the lamp is securely locked against any movement whatever by a simple turning of a single element.

Various changes in the construction and arrangement of the several parts may be employed without departing from the spirit of my invention as disclosed in the appended claims.

Having thus described my invention, what I claim as new and desire to secure by Letters Patent is:

1. A focusing device comprising a base, a seat thereon screw-threaded on its exterior, a spherical member to fit against said seat and having an opening to receive a lamp socket slidably, said spherical member being provided with slits extending from each end past the middle thereof and terminating short of the opposite end, and a clamping ring threaded onto said seat and having a flange to engage the end of the spherical member opposite the seat, for clamping the spherical member tightly against the seat, whereby both ends of the spherical member are contracted to grip the lamp socket.

2. A focusing device, comprising a spherical element having an opening to receive a lamp socket and being provided with slits extending inwardly from each end past the middle thereof and terminating short of the opposite end, and constructed of spring metal, and means engageable with each end of the spherical member for contracting the same whereby both ends of the spherical member are made to grip the lamp socket.

JOHN F. PAGENDARM.
